(57) **CLAIM**

The ornamental design for a carburetor/throttle body, as shown and described.

DESCRIPTION

FIG. 1 is a front, top, and right side perspective view of a carburetor/throttle body with broken lines illustrating only the environment and forming no part of the claimed design.

FIG. 2 is a top view of the carburetor/throttle body.

FIG. 3 is a right side elevational view of the carburetor return spring housing; and,

FIG. 4 is a front elevational view of the carburetor/throttle body.

1 Claim, 4 Drawing Sheets

FIG-2

FIG 4
